STENCIL DEVICE

Adolph Buschow, New York, N. Y.

Application January 6, 1939, Serial No. 249,553

2 Claims. (Cl. 101—125)

This invention in general relates to multigraphing apparatus and more particularly to an automatic inking stencil device, having for its principal object the provision of certain desired improvements over the stencil device shown in Patent No. 2,052,864 to Borowetz, in the way of a simplified, more economical and rugged construction, and a more facile operation in use.

Another object of the invention is to provide in 10 a device of the kind indicated, an improved, adjustable, pressure-distributing diaphragm particularly designed and adapted to achieve an even distribution of ink in the normal functioning of the device.

15 It is also an object of the invention to provide a stencil device of generally improved construction, whereby the device will be simple, durable and inexpensive in construction, as well as convenient, practical, serviceable and efficient in its use.

20 With the foregoing and other objects in view, which will appear as the description proceeds, the invention resides in the combination and arrangement of parts, and in the details of construction hereinafter described and claimed, and will be best understood by reference to the drawing wherein:

Figure 1 is a perspective view of an embodiment of the invention, the cover being removed for the purpose of clearer illustration.

30 Fig. 2 is a longitudinal sectional view, taken on the line and as viewed in the direction of the arrows 2—2 of Figure 1; and

Fig. 3 is a transverse sectional view, taken on the line and as viewed in the direction of the arrows 3—3 of Figure 1.

For the purpose of illustrating the invention, I have shown one form thereof which is at present preferred by me since the same has been found in practice to give satisfactory and reliable results, but it is to be understood that the various instrumentalities composing the invention can be variously arranged and organized, and that the invention is not limited to the precise arrangement and organization of the instrumentalities as herein shown and described.

45 Referring now to the drawing wherein similar characters of reference indicate corresponding parts in the several views of the preferred form of the invention, the numeral 12 designates a metal casing formed principally of a plate or sheet of suitable metal such as brass, aluminum, rustless iron or the like, and bent to provide an arcuate bottom 13 having uniformly distributed 50 perforations (not shown) and integral side walls

14, 15. To the outer edge of the said bent sheet, arcuately stamped plates or sheets of metal similar to that of the bottom member 13 and forming the end walls 16, 17 of the casing 12, are suitably welded or secured.

To the end walls 16, 17 angle brackets 18, 19 respectively are welded or otherwise suitably secured. Adjusting screws 21, 22 are threadedly engaged in the brackets 18, 19 and have the ends of their threaded stems similarly engaged in pressure shoes or members 23, 24 whose arcuate lower edges are fastened to the upper surface of an arcuately formed metal sheet 25 lying in substantial parallelism and in spaced relation to the bottom 13, and which serves, in coaction with other elements, as an adjustable diaphragm to control the application of ink through the perforations of the bottom 13, as hereinafter described.

The straight ends of the curved sheet, which is preferably formed of metal similar to that of the bottom member 13 and normally corrosion-proof to the printing liquids customarily employed, are attached by rivets 26 and metal strips 27, 28 to the inner ends of comparatively narrow strips of flexible material 29, 31 preferably neoprene, an artificial rubber composition having characteristics rendering it impervious to the ordinarily deleterious action of the greasy inks frequently employed in mimeographing. The outer and opposite end of each strip of neoprene is in turn fastened to an adjacent inner portion of one of the side walls 14, 15 by narrow metal strips 32, 33 and rivets 26.

The curved ends of the sheet 25, in a manner similar to that described in the preceding paragraph, are fastened to substantially curved or arcuate strips of neoprene 34, 35 by arcuate metal strips 36, 37 and coacting rivets 26, the outer edges of the last-mentioned strips of neoprene being secured to the end walls 16, 17 by the in-turned edges of the straight strips 32, 33 as at 38, and by arcuate metal strips 39 and coacting rivets. All of the strips referred to above are preferably of metal having the same characteristics as the bottom member 13 and the diaphragm 25.

It is to be understood that the securing of the neoprene to the metal sheet 25 in the manner indicated, provides an improved diaphragm forming one of the principal features of the invention and assures a liquid-tight seal in the space or reservoir 41 between the inclosing walls and bottom of the casing 11, and the said diaphragm.

The reservoir 41 in which the supply of ink

is retained, may be replenished with fresh ink through the filler pipe 42 which is secured to and registers with an opening 43 in a shoe 44 fastened to the upper surface of the sheet 25 which forms a part of the diaphragm mentioned above. The pipe 42 is normally closed by a cap 45 threadedly secured thereon. Longitudinally extending flanges 46, 47 are secured to the upper sides of the walls 14, 15 and serve, in conjunction with clips (not shown) to retain the stencil (not shown) operatively against the exterior of the bottom member 13.

In operation, the stencil assembly, generally consisting of a sheet of cloth and a prepared impression sheet, is engaged against the outer surface of the arcuate bottom 13 and secured at its ends to the flanges 46, 47 on the side walls 14, 15 by clips (not shown). A supply of ink is placed in the reservoir 41 preferably in quantity sufficient to fill the space between and to contact the opposing surfaces of the bottom 13 and the diaphragm sheet 25, and the adjusting screws 21, 22 turned sufficiently to slightly depress the diaphragm formed by the sheet 25 and the attached neoprene strips. The screw cap 45 is next tightly replaced on the filler pipe 42 and the adjusting screws 21, 22 turned in the reverse direction to permit the diaphragm mentioned above to rise to the normal position shown in Figures 2 and 3, thereby creating a partial vacuum in the reservoir 41 which is essential to preventing an excessive seeping of ink through the perforations of the bottom member 13 before actual operation. Mimeograph copies may now be produced by rocking the device over the material engaged by same to effect the force feeding of the ink through the perforations of the bottom 13 and thence through the stencil assembly, in the known manner. As the supply of ink becomes depleted, the adjusting screws 21, 22 are turned from time to time in order to maintain the diaphragm in normal contact with the supply of ink in the reservoir or fountain 41.

My improved multigraphing device, it may be pointed out, particularly lends itself to quantity production by reason of the comparatively few parts entering into its construction, and the manufacture of the majority of these by die stamping processes.

It is to be understood that the invention may be embodied in other specific forms without de-

parting from the spirit or essential attributes thereof, and it is therefore desired that the present embodiment be considered in all respects as illustrative and not restrictive, reference being had to the appended claims rather than to the foregoing description to indicate the scope of the invention; and it will be further understood that each and every novel feature and combination present in or possessed by the mechanism herewith disclosed, forms a part of the invention included in this application.

What I claim as new and desire to secure by Letters Patent is:

1. In a stencil device of the character described, the combination of a casing, a perforated plate serving as the bottom of said casing and having integral upwardly-extending walls providing opposing sides for the casing, a pair of arcuately fashioned plates secured to the first-mentioned plate and providing end walls 20 for the casing, a metallic diaphragm yieldingly mounted within the casing, said diaphragm being fastened to longitudinally extending flexible strips, means for fastening the strips to the casing, a reservoir inclosed between the diaphragm 25 and the adjacent peripheries of the first and second mentioned plates, and manually operable means adjustably connected to the end walls and to the diaphragm for adjusting said diaphragm in a plurality of predetermined positions. 30

2. In a stencil device of the character described, the combination of a metallic casing, said casing having a perforated arcuate bottom, a diaphragm yieldingly supported in parallel relation to and within the casing, said diaphragm consisting of a metallic plate and flexible means movably connecting the plate to opposite sides of the casing, a reservoir inclosed between the diaphragm and the adjacent inner periphery of the casing, means fastened to the plate and communicating with the reservoir for supplying said reservoir with ink, pressure-applying and relieving means fastened to opposite portions of the diaphragm, and manually operable, threaded means adjustably connected to the casing and the said last-mentioned means, for moving the diaphragm relatively to the said adjacent periphery of the casing and securing the diaphragm in a plurality of predetermined positions. 40

ADOLPH BUSCHOW. 50
